(57) **CLAIM**

The ornamental design for power supply unit, as shown and described.

DESCRIPTION

The patent or application file contains at least one drawing executed in color. Copies of this patent or patent application publication with color drawing(s) will be provided by the Office upon request and payment of the necessary fee.

1. Power supply unit

1.1: Perspective

1.2: Front

1.3: Back

1.4: Left

1.5: Right

1.6: Top

1.7: Bottom

1. Title of the design product: Power supply unit. 2. Purpose of this design product: The present design product is used for storing and outputting electric energy. 3. Design point of this design product: The shape of the design. 4. Picture or photograph that best embodies the design point of this design: FIG. 1.1. 5. No claim is made to the color or material shown. 6. The portions of the power supply unit shown by red color form no part of the claimed design.
